[57]**CLAIM**

The ornamental design for an integrated information appliance simultaneously capable of telephone and data communication, as shown and described.

DESCRIPTION

FIG. 1 is a top and left side perspective view of an integrated information appliance showing my new design in closed mode for using as a telephone;

FIG. 2 is a front view thereof;

FIG. 3 is a rear view thereof;

FIG. 4 is a left-side elevation view thereof;

FIG. 5 is a right-side elevation view thereof;

FIG. 6 is a plan view thereof;

FIG. 7 is a bottom view thereof; and,

FIG. 8 is a top and left side perspective view of an integrated information appliance showing my new design in opened mode for data communication.

1 Claim, 8 Drawing Sheets
